UNITED STATES PATENT OFFICE.

ANE P. SCHAT, OF THE HAGUE, NETHERLANDS.

AUTOMATICALLY-BRAKED DAVIT.

1,423,739.

Specification of Letters Patent. Patented July 25, 1922.

Application filed February 1, 1921. Serial No. 441,618.

To all whom it may concern:

Be it known that I, ANE P. SCHAT, a citizen of Holland, residing at The Hague, in the Province of Zuid Netherland and Kingdom of the Netherlands, have invented certain new and useful Improvements in Automatically-Braided Davits, of which the following is a specification.

My invention relates to davits—both automatic and non-automatic—for swinging life-boats overboard, and is related to my pending applications #442,032, #390,603, #286,018, and #353,907.

In davits of this character serious difficulties are at times encountered by reason of certain conditions which frequently obtain at sea. For instance, in times of disaster, it is often desirable to put life-boats overboard at either or both sides of a ship that has a heavy list. Now, if the davits be so arranged as to automatically swing the boats out properly when the ship rests on a level keel, then the davits on the upper side of the ship will not swing them out automatically at all against a heavy list, while the davits on the lower side of the ship will fairly leap overboard with dangerous swiftness and power. If the davits be so arranged that they will put boats over the upper side of the ship against a heavy list, that will make it all the worse for the davits at the lower side of the ship, to say nothing of the fact that, in this latter case, they will put boats over on both sides entirely too swiftly when the ship rests on a level keel.

One of the objects of the present invention is to provide braking mechanism adapted to lock a davit (whether it be automatic or non-automatic) under the influence of the weight of the boat or other load suspended therefrom, the braking mechanism being preferably automatic in its action.

A specific object is to provide a davit having braking means adapted to hold it normally locked against rotation, and also having means whereby the weight depending from the davit normally operates to lock the davit or brake it to a stand-still; these two braking means being adapted to either work together or separately, the davit being permitted in either case to rotate by independent mechanism adapted to ease up the braking pressure on the davit sufficiently to permit it to rotate with as much freedom or as much restriction as may be desired.

Another object is to provide braking

means which, while adapted to very gently release the davit to permit its outboard movement, will yet promptly engage and stop it at any point desired.

Other objects will appear in the subjoined description.

The invention consists in certain novel features of construction and arrangement of parts, as will be hereinafter described and claimed, reference being had to the accompanying drawings, in which—

Fig. 1 is a side elevation of one form of my davit with a lifeboat depending therefrom. Fig. 2 is a section of Fig. 1 taken at the upper side of the brake disc 3 in a plane parallel with said disc, to show a plan view of the braking mechanism located in the davit frame. Fig. 3 is a side elevation showing an enclosed brake-applying spring; and Fig. 4 is a slight modification of Fig. 3.

The davit 1 has its upper and lower parts disposed at an angle to each other, with the lower portion rotatably received in a frame 2, and inclined outwardly toward the side of the ship, to impart to the davit a tendency to swing outboard by gravity.

The brake disc 3 is rigidly secured to the davit preferably adjacent its lower bearing, and is provided with a central peripheral groove 3^a having its sides inclined inwardly toward each other to cooperate with the wedge-shaped brake blocks 4 located on diametrically opposite sides of the brake disc 3, and adapted to be forced into the groove 3^a by means of brake levers 5, which are pivoted at their inner ends to bearings 6 rigidly supported on the davit frame 2, and connected at their opposite ends with the toggle 7, which is in turn pivotally connected at its central joint with the block 8, said block being bifurcated at its inner end to receive said joint, and pivotally connected near its other end to the lower end of a bell-crank lever 9 formed of two parallel plates which are adapted to rock on a pivot 10 carried by supports 11 rigidly mounted on a channel bar 12 which is in turn supported on the frame 2.

The pivot 10 is held in operative position on the supports 11 by means of small plates 11^a, which are suitably secured in flat engagement with the outer faces of the supports 11, with their edges extending into the transverse grooves 10^a in the slightly projecting ends of said pivot.

The upper end of the bell-crank lever 9 is engaged by the lower end of a cable or load

rope 13, while the upper block 14 of the tackle, instead of being connected to the davit head in the usual manner is suspended from the other end of said load rope or cable 5 13 which is led up from said block over the sheave 15 at the upper end of the davit, and down over the sheave 16 at the bend thereof, and on to the bell-crank lever.

The boat-fall runs from the upper tackle 10 block 14 over a sheave 17 on the same shaft with the sheave 16, said shaft being carried by a strap 18 adjustably secured around the davit. The boatfall may be led downwardly 15 from the sheave 17 and be laid on the cleat 20 in the usual manner.

The block 8 which at its bifurcated end has pivotal connection with the toggle 7, has, at its other end, swivel connection with the screw spindle 21, which is provided with a 20 screw thread of great pitch, and is received in an elongated brass nut 22 suitably secured to the frame 2. This nut is internally threaded to correspond to the threads on the spindle, said cooperating threads on the spindle 25 and nut being of so great a pitch that only slight end pressure on the spindle 21 will be required to cause the same to rotate in the nut, which arrangement not only causes the spindle 21 to be non-self-braking in the nut 30 22, but also causes a slight rotation of said spindle 21 to impart to the same a comparatively great longitudinal movement, whereby when the lever 23 is rotated forwardly only slightly, a sufficient longitudinal movement 35 will be imparted to the spindle 21 to promptly apply the brakes, whereas on the other hand, when the lever 23 is released, the inward pull imparted to said spindle by the effort of the toggle to straighten itself under 40 the strain imposed upon it by the application of the brakes will cause the device to operate very promptly in releasing the brakes.

At its inner end the screw spindle 21 is squared for the reception of said controlling 45 handle or lever 23.

Small plates 24 rigidly secured to the bottom bars of the frame 2 and provided with adjusting bolts 25 adapted to engage the brake blocks 4, cause both of said blocks to be 50 come disengaged from the groove 3^a of the brake disc at approximately the same time when the levers 5 are moved in a direction to unlock the brake. From the foregoing it 55 will be seen that the entire weight of the load is suspended from the cable 13 and utilized to apply the brake to the davit, always in proportion to the weight of the load, whether the boat be empty or fully loaded; the adjustments of the parts being such that 60 the weight of the empty boat brakes the davit to a stand-still, and when the boat is loaded, it will be additionally braked in proportion to the added weight, so that the davit always remains normally locked when 65 the boat is depending therefrom, and can

only rotate when the braking power of the load is, to a greater or less degree, counteracted by a proper rotation of the hand lever 23. Therefore, when the parts are once properly adjusted, no readjustments are necessary for changes of load.

By a proper manipulation of the hand lever 23, the davit is permitted to swing out as gradually as may be desired, and when the hand lever is released the davit is again instantly locked against rotation, since as already referred to the pitch of the threads on the screw stem 21 is so great that said stem is easily rotated when pressed longitudinally outward by the weight of the load through 80 the bell-crank lever 9, and therefore said threaded stem does not offer any appreciable resistance to the prompt automatic operation of the brake, as it would do if its threads were of much less pitch.

From the foregoing, it will be seen that however strong the winds, or however badly the ship may be rolling and pitching, or however adverse other conditions may be, the davit will always be firmly held against rotation, until permitted to rotate by a proper turn of the hand lever 23.

But with my device as thus far described, the brake would be released when the boat rests upon the water, and the davit would, therefore be no longer held against swinging back and forth. To prevent this, I provide the following additional mechanism for imposing a constant load on the bell-crank lever:—The bell-crank lever is provided with a downwardly extending portion 26 adapted at its lower end to be engaged by a tension spring 27, said spring being threaded at its other end 27^a which extends out through a plate 28 of the frame, and is provided with jamb nuts 29 for regulating the tension of said spring to cause the same to apply the braking mechanism independently of the load, so that the davit will always be braked against swinging back and forth, even when the boat is no longer supported thereupon, but is resting on the water or on the chocks.

This spring may be made sufficiently strong if desired, to take the place of the load and load rope 13 in applying the braking mechanism, in which case the load rope arrangement may be dispensed with, and the boat suspended from the davit in the usual manner. With this arrangement it is only necessary to adjust the spring 27 to hold the davit braked to a stand-still when the boat is fully loaded. The boat can then be lowered by the hand lever 23, just as when the weight of the load is utilized to operate the brakes.

In order to shield the brake-applying spring from the corroding action of salt air and salt water, the same may, if desired, be enclosed in a metallic box 30, as illustrated

in Fig. 3, in which the box is shown provided with flanges 31 for rigidly securing the same to the ship's deck, and has a cover 32. Extending longitudinally of the box is 5 a rod 33 having a reduced inner end 34 extending through a supporting standard 35. The rod 33 carries a compression spring 36, and extends out through the end of the box, and by means of a link 37 is pivotally connected with the downward extension 26 of 10 the bell-crank lever 9 of the braking mechanism. At its inner end, adjacent the reduced portion 34, the rod 33 is threaded to receive the jam-nuts 38 for regulating the 15 tension on the spring 36.

The standard 35 is provided with a base 39 for removably securing said standard to the box 30.

The rod 33 and the link 37, as well as 20 many other parts of the device, are preferably made of bronze or other metal which offers unusual resistance to the corrosive action of salt air and salt water.

The box 30 is provided with a packing 25 box 40 for the projecting end of the rod 33, whereby the outer air is entirely excluded from the spring and no salt water can possibly reach it. Moreover, the box may be filled with oil, if desired.

It has already been pointed out that either 30 the load alone or the spring alone may be made to operate the braking mechanism to lock the davit against rotation, and that in either case the braking pressure may be regulated by the hand lever 23 to permit the 35 davit to revolve. And it is also apparent that if need arises the lever 23 may also be used to apply the brakes with great force either independently of, or in conjunction 40 with, the other brake-operating mechanism. It therefore only remains to be added that the parts may be so adjusted that neither the load alone, nor the spring alone, will lock 45 the davit, but that the combined action of both will be required to brake it in the manner desired. In that case, regulating one of the parts, as for instance the spring will regulate the force of the entire braking mechanism of the davit.

The operation of the device is very simple: If the weight of the load be depended 50 upon chiefly to brake the davit, it will be seen that as soon as the boat is released from the chocks and depends from the load rope 55 13, the bell-crank lever is moved in a direction to apply the brakes so that the davit cannot rotate. A proper movement of the hand lever 23 counteracts the braking force 60 of the load on the bell-crank lever and permits the davit to rotate. The moment the lever 23 is released, the brakes are again applied with the full braking power of the load. When the boat has been lowered and 65 rests upon the water, the spring 27 operating through the bellcrank lever 9 still ap-

plies the brakes with sufficient force to keep the davit from oscillating.

If the boat be suspended from the davit in the ordinary manner, and the spring 27 be employed alone for braking the davit, the 70 spring should be made strong enough to apply the brakes with sufficient force to hold the davit against rotation when supporting its maximum load, leaving the device still dependent as before, upon the easing up of the 75 braking force by the hand lever 23, in order to permit the boat to swing out.

While the drawings show a davit inclined 80 toward the sides of the ship to cause it to swing outboard by gravity, attention is called to the fact that my invention is 85 equally applicable to davits which are not within themselves automatic, but are adapted to be swung out by the weight of the load alone, as, for instance, in my copending application #389,445.

In Fig. 4 I have shown a slight modification 90 of the construction illustrated in Fig. 3, whereby the link 37 and the packing box 40 may be dispensed with.

In this modification I have provided the rod 33 with a collar or sleeve 41 having a central longitudinal bore snugly fitting said rod, said sleeve being also provided with a comparatively broad, flat head 42 95 against the inner face of which the end of the spring 36 abuts to hold the outer face of said head in close engagement with the end of the box 30 around the opening 30a therein through which the rod 32 projects. 100 The lower end of the extension 26 of the bellcrank lever is provided with a slot 43 which engages the pin 44 in the outer bifurcated end of the rod 33, and permits said extension 26 to rock on its pivot 45 without 105 imposing lateral strain upon the projecting end of said rod 33.

The pin 44 may be provided with a friction roller if desired.

With the above arrangement the box 30 110 will have approximately the same air pressure inside of it as outside of it, and will be practically air tight, because there will always be a film of oil surrounding the rod 33 between the same and the inside of the 115 sleeve 41, and between the head 42 of the collar and the end of the box 30 around the opening 30a; and this film of oil will form a liquid packing, as it were, that will prevent the entrance of air or salt water into 120 the box.

In order to insure a supply of oil always being on the rod 33 adjacent the inner end 125 of the sleeve 41, I have provided at that point a lubricating wick 46, preferably of fibrous material, which is tied around the rod and extends down and rests on the bottom of the box, so that as long as there is any oil at all in the box, the rod 33 will be lubricated.

While my braking mechanism has exceptional value for automatic davits, it is not limited to davits of this class, nor does it require in any case that guy ropes shall be fitted to the davit heads.

Having now described my invention and shown one particular embodiment of the same, what I claim as new and desire to protect by Letters Patent is:—

- 5 10. 1. In a device of the character described, a davit adapted to rotate outboard and in-board; and means for utilizing the weight of the load to brake the davit.
- 15 2. In a device of the character described, a davit adapted to rotate outboard and in-board; means for utilizing the weight of the load to brake the davit against rotation; and independent means for controlling the braking mechanism of the davit.
- 20 3. In a device of the character described, a davit adapted to rotate outboard and in-board; braking means for normally locking the davit against rotation; and independent means for controlling said braking means.
- 25 4. In a device of the character described, a davit adapted to rotate outboard and in-board; and means for utilizing the weight of the load to brake the davit against rotation, in combination with additional means for normally braking the davit against rotation; and independent means for controlling the braking mechanism of the davit.
- 30 5. In a device of the character described, a davit having a cooperating tackle; braking mechanism for the davit; a flexible member connected with the braking mechanism to operate the same and extending from thence over the top of the davit with the upper block of the tackle suspended therefrom; whereby to apply said braking mechanism to the davit in proportion to the weight of the load suspended from the tackle; and independent means for controlling said braking mechanism.
- 35 45 6. In a device of the character described, a davit adapted to swing outboard under the influence of its load; means for utilizing the weight of the load to brake the davit against rotation; and independent means for controlling the braking mechanism of the davit.
- 50 7. In a device of the character described, a davit adapted to swing outboard by gravity; braking means for normally locking the davit against rotation; and independent means for controlling said braking means.
- 55 8. In a device of the character described, a davit adapted to swing outboard under the influence of its load; and means for utilizing the weight of the load to brake the davit against rotation, in combination with additional means for normally braking the davit; and independent means for controlling the braking mechanism of the davit.
- 60 9. In a device of the character described, a davit adapted to rotate outboard by grav-

ity; and braking means adapted to normally lock the davit against rotation, in combination with additional means for utilizing the weight of the load to brake the davit against rotation; and independent means for controlling the braking mechanism of the davit.

10. In a device of the character described, a davit adapted to rotate outboard under the influence of its load; braking means for normally locking the davit against rotation; and independent means for controlling said braking means.

11. In a device of the character described, a davit adapted to swing outboard under the influence of its load; braking mechanism for the davit; a flexible member connected at one end to the load and arranged to hold the same suspended from the davit, and secured at its other end to the operating mechanism of the brake, whereby the braking mechanism is applied to the davit in proportion to the weight of the load; and manually operated means for regulating said braking mechanism.

12. In a device of the character described, a davit adapted to swing outboard under the influence of its load; braking mechanism for the davit; a flexible member adapted at one end to hold the load suspended from the davit, and operatively connected at its other end to the brake operating mechanism, whereby to apply the brakes to the davit in proportion to the weight of the load; a loaded lever cooperating with said brake operating mechanism to additionally apply the brakes to the davit; and manually operated means for controlling the braking mechanism of the davit.

13. In a device of the character described, a davit adapted to swing outboard under the influence of its load; braking mechanism for the davit including a bellcrank lever for applying the brakes; a flexible member adapted at one end to support the load suspended from the davit, and operatively connected at its other end to said bellcrank lever, whereby to apply the brakes in proportion to the weight of the load; and manually operated means also engaging said bellcrank lever for regulating the power of the load thereupon.

14. In a device of the character described, a davit adapted to swing outboard under the influence of its load; braking mechanism for the davit including a bellcrank lever for applying the brakes; a flexible member adapted at one end to support the load suspended from the davit, and operatively connected at its other end to said bellcrank lever, whereby to apply the brakes to the davit in proportion to the weight of the load; a loaded lever also connected with said bellcrank lever to additionally apply the brakes to the davit; and manually operated means for counteracting the influence of the load and

of the loaded lever upon the braking mechanism.

15. In a device of the character described, a davit adapted to swing outboard under the influence of its load; braking mechanism for the davit; a spring operatively connected with the braking mechanism and arranged to normally apply the brakes; a housing for said spring; a shaft received in 10 said housing with the spring received around the shaft, the housing having an opening with the end of the shaft projecting out therethrough for engagement with the braking mechanism; and a sleeve on the 15 enclosed part of said shaft, the spring being arranged to press the end of the sleeve against the housing around the opening therein through which the shaft projects.

16. In a device of the character described, 20 a davit adapted to swing outboard under the influence of its load; braking mechanism for the davit; a spring operatively connected with the braking mechanism and arranged to normally apply the brakes; a closed housing for said spring said housing having approximately the same air pressure inside of it as outside of it; a shaft in said housing with the spring received around the shaft; the housing having an opening with the end 25 of the shaft projecting out therethrough for engagement with the braking mechanism; a sleeve on the enclosed part of said shaft, the spring being arranged to press the end of the sleeve against the housing around the 30 opening therein through which the shaft projects; said housing being adapted to hold a liquid packing for sealing the housing around the opening therein; and means for conducting said packing from the bottom of 35 the housing to the exposed surface of the shaft.

17. In a device of the character described, 40 a davit adapted to swing lifeboats outboard and inboard; braking mechanism for the davit including a spring; a housing for said spring; a shaft received in said housing with the spring and adapted to cooperate therewith in the operation of the braking mechanism; said housing having an opening with 45 the end of the shaft projecting out therethrough for engagement with the other parts of the braking mechanism; and a wick 50 engaging said shaft adjacent the opening therein and extending down to the bottom 55 of the housing.

18. In a device of the character described, 60 a davit adapted to rotate under the influence of its load; braking mechanism for the davit to resist its tendency to rotate, said mechanism comprising a disc secured to the davit; 65 brake levers on opposite sides of the disc, said levers being pivoted at their shorter ends to fixed bearings and connected at their longer ends by a toggle; braking means connected with the toggle for normally applying

the brakes; and independent means for controlling said brake applying means.

19. In a device of the character described, a davit adapted to rotate under the influence of its load; braking mechanism for the davit 70 to resist its tendency to rotate, said mechanism comprising a disc secured to the davit; brake levers on opposite sides of the disc, said levers being pivoted at their shorter ends to fixed bearings and connected at their 75 longer ends by a toggle; means connected with the toggle for automatically operating the brakes; and manual means for controlling said automatic brake applying means.

20. In a device of the character described, 80 a davit adapted to rotate under the influence of its load; braking mechanism for the davit to resist its tendency to rotate, said mechanism comprising a disc secured to the davit; 85 brake levers on opposite sides of the disc, said levers being pivoted at their shorter ends to fixed bearings and connected at their longer ends by a toggle; means connected with the toggle for utilizing the weight of the boat to apply the brakes; and manual 90 means for controlling said brake applying means.

21. In a device of the character described, a davit adapted to rotate under the influence of its load; braking mechanism for the davit 95 to resist its tendency to rotate, said mechanism comprising a disc secured to the davit; brake levers on opposite sides of the disc, said levers being pivoted at their shorter ends to fixed bearings and connected at their 100 longer ends by a toggle; means connected with the toggle for normally applying the brakes; additional means for utilizing the weight of the load to apply the brakes in proportion to said weight; and manual 105 means for independently controlling said brake applying means.

22. In a device of the character described, 110 a davit for supporting a lifeboat and adapted, when the boat is freely suspended thereupon, to swing outboard with the boat automatically; braking mechanism for the davit to resist its tendency to rotate, said mechanism comprising a disc secured to the davit and provided on its periphery with a V-shaped annular groove; braking levers on opposite sides of the disc pivoted at their shorter ends to fixed bearings and pivotally connected at their longer ends by a toggle; 115 brake blocks pivotally supported by said brake levers, and having their braking faces formed V-shaped and adapted to be received into the V-shaped groove of the brake disc; means for automatically operating the toggle to apply the brake shoes in said 120 groove; and manual means for independently controlling said brake applying means.

23. In a device of the character described, 125 a davit for supporting a lifeboat, and adapted, when the boat is freely suspended there- 130

upon, to swing outboard with the boat automatically; braking mechanism for the davit to resist its tendency to rotate, said mechanism comprising a disc secured to the davit 5 and provided on its periphery with a V-shaped annular groove; brake levers on opposite sides of the disc pivoted at their shorter ends to fixed bearings and pivotally connected at their longer ends by a toggle; 10 brake blocks pivotally supported by said brake levers, and having their braking faces formed V-shaped and adapted to be received into the V-shaped groove of the brake disc; means for automatically operating the toggle 15 to apply the brake shoes in said groove; and positive means for simultaneously disengaging the brake blocks from the V-shaped groove of the brake disc when the brake levers are released.

20 24. In a device of the character described, a davit for supporting a lifeboat, and adapted, when the boat is freely suspended thereupon, to swing outboard with the boat automatically; braking means for the davit to resist its tendency to rotate, said means comprising a disc secured to the davit, and provided on its periphery with a V-shaped annular groove; brake levers on opposite sides 25 of the disc pivoted at their shorter ends to fixed bearings and pivotally connected at their longer ends by a toggle; brake blocks pivotally supported by said brake levers, and having their braking faces formed V-shaped and adapted to be received into the V-shaped 30 groove of the brake disc; means for automatically operating the toggle to apply the brake shoes in said groove; and yielding means for simultaneously forcing the brake blocks each outwardly in a direction from 35 the centre of the brake disc when the brake levers are released.

40 25. In a device of the character described, a davit for supporting a lifeboat, and adapted, when the boat is freely suspended thereupon to swing outboard with the boat automatically; braking means for the davit to resist its tendency to rotate, said means comprising a disc secured to the davit, and provided on its periphery with a V-shaped annular groove; brake levers on opposite sides 45 of the disc pivoted at their shorter ends to fixed bearings and pivotally connected at their longer ends by a toggle; brake blocks pivotally supported by said brake levers, and having their braking faces formed V-shaped and adapted to be received into the V-shaped 50 groove of the brake disc; means for automatically operating the toggle to apply the brake shoes in said groove; and spring plates fixedly secured at one end and adjustably connected at their free ends with the brake shoes and adapted to yieldingly 55 resist the inward movement of said brake shoes, whereby said shoes are simultaneously moved automatically outward in a direction 60

from the centre of the disc when the brake levers are released.

26. In a device of the character described, a davit adapted to rotate under the influence of its load; braking mechanism for the davit to resist its tendency to rotate, said mechanism comprising a disc secured to the davit; brake levers on opposite sides of the disc, said levers being pivoted at their shorter ends to fixed bearings and connected at their 70 longer ends by a toggle; a bell-crank lever connected with the toggle and with the load and adapted to be operated by the load to apply the brakes; and manual means, including a brake pin having a non-self-braking 75 thread, for controlling said bell-crank lever to counteract the braking force imposed thereupon by the weight of the load.

27. In a device of the character described, the combination with a crane and a co-operating tackle, of means for supporting the upper block of the tackle at a variable distance from the top of the crane; and means for utilizing the movement of said upper tackle block toward and from the 80 top of the crane to operate mechanism connected with the crane.

28. In devices of the character described, the combination with a davit and its co-operating tackle, of a flexible member adapted to support the upper block of the tackle suspended from the davit top and secured to a movable member adapted to be actuated by the tension of said flexible member.

29. In a device of the character described, the combination with a davit and a co-operating tackle having an operating fall extending therefrom to raise and lower the lower tackle block, of an independent member adapted to engage and support the upper block of the tackle at a variable distance from the davit top; and means for utilizing the movement of said upper tackle block toward and from the top of the davit to operate mechanism connected 105 with the davit.

30. In a device of the character described, the combination with a crane and a co-operating tackle, of a flexible member adapted to support the upper tackle block suspended from the crane; power operated mechanism adjacent the crane, said flexible member being operatively connected therewith.

31. In a device of the characters described, a davit having a co-operating tackle; braking mechanism for the davit; a flexible member operatively connected with the braking mechanism and extending over the top of the davit with the upper block of the tackle suspended therefrom, whereby to utilize the weight supported by the tackle, to operate the davit brake.

32. In a device of the character described, a davit having braking mechanism; means for normally applying said mechanism to 120

the davit; a flexible member connected with said braking mechanism and adapted to also apply the same to the davit, and extending over the top of the davit with the upper 5 tackle block suspended therefrom, whereby to use the weight of the load to cooperate with said normal braking means to apply the braking mechanism to the davit; and independent means for controlling said 10 braking mechanism.

33. In a device of the character described, a davit adapted to rotate on its longitudinal axis and inclined outwardly toward the water to adapt it to rotate outboard by 15 gravity; means for utilizing the weight of the load to brake the davit against rotation; and additional means for regulating said braking means and for controlling the same independently of the weight of the load.

34. In a device of the character described, the combination with a davit adapted to rotate inboard and outboard on its longitudinal axis, of means for braking the rotation of the davit, said means including a 20 plurality of braking members adapted to 25 move simultaneously into braking or releasing position.

35. In a device of the character described, the combination with a davit adapted to ro-

tate outboard and inboard on its longitudinal axis, of means for braking the rotation of the davit, said means including a brake disc rotatable with the davit; and approximately parallel brake levers on diametrically opposite sides of the disc adapted 30 to be moved in substantially parallel relation toward and from the centre of the disc 35 to apply and release the brakes.

36. In a device of the character described, the combination with a davit adapted to rotate inboard and outboard on its longitudinal axis, of braking means comprising a brake disc rotatable with the davit; brake shoes on diametrically opposite sides of the disc; brake levers for supporting said shoes, 40 said levers being on opposite sides of the disc and disposed approximately parallel with each other and having one end pivotally mounted and the other end hinged to rods 45 nearly in alinement with each other when the shoes are in position to engage the 50 brake disc; and a member pivotally connected with said rods for actuating the brakes.

In testimony whereof I affix my signature.

ANE P. SCHAT.
